UNITED STATES PATENT OFFICE.

SNOWDEN B. REDFIELD, OF EASTON, PENNSYLVANIA, ASSIGNOR TO INGERSOLL-RAND COMPANY, OF JERSEY CITY, NEW JERSEY, A CORPORATION OF NEW JERSEY.

DISCHARGE UNLOADER.

Application filed March 4, 1927. Serial No. 172,718.

This invention relates to unloading devices, but more particularly to a discharge unloader for compressors and the like.

One object of the invention is to vent the cylinder of a compressor to atmosphere during the unloaded period of the compressor.

Other objects will be in part obvious and in part pointed out hereinafter.

10 The invention consists of the combination of elements and arrangement of parts substantially as hereinafter described and claimed and illustrated in the accompanying drawings, in which.

15 Figure 1 is a sectional elevation of a portion of a compressor cylinder having the invention applied thereto, and

20 Figure 2 is a sectional elevation of the manipulating valve taken through Figure 1 on the line 2--2 looking in the direction of the arrows.

25 Referring to the drawings, A designates the cylinder of a compressor supporting at one end a head B. The cylinder A may be the final stage cylinder of a multi-stage compressor and is preferably provided with a bushing C to receive slidably the piston D.

30 The head B may be secured to the cylinder A in any suitable manner and in this instance the head B is provided with a bore E in alignment with the bushing C to receive slidably the end of the piston D.

35 Seated on the head B is an intake unloader designated generally by F. The intake unloader is like that described in detail in the copending application of S. B. Redfield, Serial No. 145,243, filed October 30, 1926, entitled "Centralized interlocking control for multi-stage compressors." The intake unloader accordingly has a plunger G actuated by a piston H for controlling the admission of pressure fluid conveyed from a lower stage cylinder through a connection J to the cylinder A.

40 The pressure fluid conveyed by the connection J passes through a passage K in the intake unloader F from whence it flows through a passage L in the intake unloader to a chamber O formed in the head B. A passage P leading from the cylinder bore E communicates with the chamber O through a port Q having at one end a seat R for an inlet valve S which controls communication between the chamber O and the passage P.

A passage T also leading from the cylinder bore E communicates with a discharge chamber U in the head B through a port V and communication between the passage T and the discharge chamber U is controlled by a discharge valve W of a well known type.

Convenient means are provided for selectively actuating the plunger G in the proper direction for preventing the admission of pressure fluid from the connection J to the passage L whenever it is desired to unload the cylinder A. These means in the present instance consists of a pipe X leading from a suitable source of pressure fluid supply (not shown) to the intake unloader F for conveying pressure fluid thereto.

A valve chest Y is in this instance interposed in the pipe X to house a throttle valve Z having a passage b to establish communication between the opposed members of the pipe X connected to the valve chest. The throttle valve Z also has a recess c in one side to establish communication between the portion of the pipe X which leads from the intake unloader to the valve chest and the atmosphere through ports d and e, said ports being located in the valve chest on opposite sides of the pipe X.

During the normal operation of the device so far described, that is, during the loaded period of the compressor, pressure fluid conveyed from a lower stage cylinder through the connection J enters the passage K and from thence flows through the passage L into the chamber O, it being, of course, understood that the plunger G is free to move from the closed position indicated in the drawing. As the piston D is retracted in the cylinder A, the inlet valve S will be raised to admit pressure fluid from the chamber O into the cylinder A through the port Q and the passage P. The pressure fluid is then discharged from the cylinder into the discharge chamber U through the port V and the passage T.

100 During the operation so far described, the throttle valve Z will occupy a position which will cut off the flow of the pressure fluid from the pipe X into the intake unloader and will open the intake unloader to the atmosphere through the pipe X, the recess c in the valve and one or both of the ports d and e. If, then it be desired to unload the

cylinder A, the throttle valve Z may be rotated to the position illustrated in the drawings. In this position of the throttle valve, pressure fluid will flow into the intake unloader F and acting upon the piston H will actuate said piston in the required direction to close the plunger G and thus cut off communication between the connection J and the cylinder A.

10. After the supply of pressure fluid to the cylinder A has been cut off by the plunger G, the piston D will, in the absence of leakage of pressure fluid into the cylinder, draw a vacuum. The difficulty of machining the cooperative surfaces of the various elements which control the admission of pressure fluid to the cylinder to fits which will absolutely prevent leakage of pressure fluid are, however, well recognized and in practice some pressure fluid at times leaks into the cylinder A during the unloaded period and is compressed therein to a higher stage and discharged into the final receiver. In order to prevent an occurrence of this kind in the present instance, a discharge unloader designated generally by f is disposed on the head B and has a passage g which communicates with the discharge chamber U through a port h in the head B. 20 At its other end the passage g communicates with a valve chamber k formed transversely through the casing o of the discharge unloader. In the present instance a passage p leading from the valve chamber k affords communication between said valve chamber and a discharge pipe q which may lead to a final receiver (not shown).

In order to prevent the pressure fluid discharged into the pipe q from again returning into the discharge chamber U, a check valve r of a well known type is disposed in one end of the valve chamber k and is normally held closed by a spring s, said spring being seated in the check valve r and bears with its outer end against a plug t which seals the end of the valve chamber and also serves to secure in position a bushing u in which the check valve r reciprocates.

50. In the opposite end of the valve chamber k is disposed a valve cage v in which is disposed a valve w to control a port x in the inner end of the valve cage v. The port x affords communication between the passage g and a bore y in the valve cage in which the valve w reciprocates. A vent z is in this instance formed in one side of the valve cage v and the casing o to afford communication between the bore y and the atmosphere.

60. The outer end of the valve w may be enlarged as at 2 to form an abutment for a piston 3 slideable in the valve cage v. Bolts 5 screwed into the end of the casing o in this instance hold the valve cage firmly in opera-

tive position. Preferably, a flange 6 is formed on the valve cage to act as an abutment for a collar 7 through which the bolts 5 extend.

Suitable means are provided to insure closing of the valve w during the time that the cylinder A is unloaded, and to that end a spring 15 is interposed between the valve w and the piston 3. In the present instance the spring is seated in a recess 16 formed in the piston 3. The recess is of sufficient depth to enable the spring to be pressed thereinto whenever the piston 3 and the valve w are in contact with each other.

A closure for the end of the valve chamber k is in this instance provided in the form of a plug 8 having a passage 9 which communicates with the bore of the bushing for conveying pressure fluid thereto, such pressure fluid being conveyed into the passage 9 by a pipe 10 secured at one end to the plug 8 and at its opposite end to the intake unloader F to communicate with the passage L in said intake unloader. In this way when the admission of pressure fluid to the cylinder A is cut off, the admission of pressure fluid to the bushing 8 will also be simultaneously cut off.

In the operation of the device, whenever the cylinder A is unloaded and therefore drawing a vacuum, any pressure fluid leaking into the cylinder bore E will be discharged into the discharge chamber U from whence it will pass through the passages h and x to act against the valve w. While the compressor is operating under these conditions, the flow of pressure fluid to the chamber k will, of course, also have been cut off. However, the spring 15 will then hold the piston 3 rearwardly against the plug 8 and will also tend to hold the valve w closed. After the pressure fluid discharged in the discharge chamber U and the various passages leading to the bore y of the valve cage reaches a value which will enable it to overcome the force of the spring 15, the valve w will be unseated and such pressure fluid will then be exhausted through the bore y and through the vent z to the atmosphere. The spring 15 by its compressive action will then promptly close the valve w and prevent atmospheric air from being drawn into the discharge chamber U on the reverse stroke of the piston.

I claim:

1. A discharge unloader for a compressor cylinder, comprising a casing adapted to be connected in the discharge line of the compressor, said casing having a passage for conveying pressure fluid from the cylinder to the discharge line, said casing having a vent affording communication between the passage and the atmosphere, and means in the casing controlling the vent, said

means being held inoperative by intake pressure fluid during the loaded period of the compressor.

2. A discharge unloader for a compressor cylinder, comprising a casing adapted to be connected in the discharge line of the compressor, said casing having a passage for conveying pressure fluid from the cylinder to the discharge line, a vent in the casing affording communication between the passage and the atmosphere, and spring pressed means for controlling communication between the passage and the vent during the unloaded period of the cylinder.

3. A discharge unloader for a compressor cylinder, comprising a casing adapted to be connected in the discharge line of the compressor, said casing having a passage forming a part of the discharge line, a vent in the casing leading from the passage to the atmosphere, a valve controlling communication between the passage and the vent, said valve being held closed by pressure fluid during the loaded period of the cylinder, and a spring tending to hold the valve in closed position during the unloaded period of the cylinder.

4. A discharge unloader for a compressor cylinder, comprising a casing adapted to be connected in the discharge line of the compressor, said casing having a passage for conveying pressure fluid from the cylinder to the discharge line, a valve chamber in the casing communicating with the passage, a vent in the casing affording communication between the valve chamber and the atmosphere, a valve in the valve chamber controlling communication between the passage and the vent, means conveying pressure fluid to the valve chamber for holding the valve closed during the loaded period of the cylinder, and a spring acting against the valve to close the valve in the absence of pressure fluid in the valve chamber during the unloaded period of the cylinder.

5. A discharge unloader for a compressor cylinder, comprising a casing adapted to be connected in the discharge line of the compressor, said casing having a valve chamber, a passage in the casing for conveying pressure fluid from the cylinder to the discharge line, said passage also communicating with the valve chamber, a vent in the casing affording communication between the valve chamber and the atmosphere, a valve reciprocable in one end of the valve chamber controlling the vent, a piston in the other end of the valve chamber adapted to be pressed against the valve by pressure fluid for holding the valve closed during the loaded period of the cylinder, and a spring between the valve and the piston tending to hold the valve closed during the unloaded period of the cylinder.

6. A discharge unloader for a compressor cylinder, comprising a casing adapted to be connected in the discharge line of the compressor, said casing having a valve chamber, a passage in the casing forming a part of the discharge line, said passage also communicating with the valve chamber, a vent in the casing leading from the valve chamber to the atmosphere, a valve in the inner end of the valve chamber controlling communication between the passage and the vent, a piston in the outer end of the valve chamber, said piston being of larger diameter than the valve, means conveying pressure fluid to the valve chamber to act against the piston for holding the valve closed during the loaded period of the cylinder, a spring between the valve and the piston to effect closing of the valve during the unloaded period of the cylinder, and means for selectively controlling the admission and exhaust of pressure fluid to and from the valve chamber.

In testimony whereof I have signed this specification.

SNOWDEN B. REDFIELD.
